ABSTRACT: A tobacco product is described which includes a 3-(2-hydroxycyclohexyl) propionic acid, delta lactone having the structure

Small amounts of this lactone enhance the flavor and aroma of the tobacco and improve the organoleptic qualities of the tobacco smoke.

1
TOBACCO PRODUCT

BACKGROUND OF THE INVENTION

Many substances are known which when added to a tobacco product improve the flavor and aroma of the tobacco smoke. Many of these substances, as for example, menthol, are highly volatile and impart to the tobacco smoke a flavor and aroma generally characteristic of the substance added. Much time and effort are devoted by the tobacco industry to develop additives which, when applied to a tobacco product, enhance the natural flavor of the tobacco as well as improve the organoleptic qualities of the tobacco smoke.

BRIEF SUMMARY

A tobacco flavorant has now been discovered which, when added to smoking tobacco, substantially enhances the natural flavor and aroma of the tobacco and improves the organoleptic qualities of the tobacco smoke.

An object of this invention therefore is to provide a flavorant for tobacco which will improve the tobacco's flavor and aroma, and the tobacco smoke's organoleptic qualities.

DESCRIPTION OF THE INVENTION

In accordance with this invention, tobacco flavor is enhanced by the addition of a saturated lactone 3-(2-hydroxycyclohexyl) propionic acid, delta lactone having the chemical structure

By incorporating small amounts of this lactone in tobacco the natural flavor and aroma of the tobacco are enhanced and the organoleptic qualities of the tobacco smoke are improved.

In carrying the invention into practice, the addition of 3-(2-hydroxycyclohexyl) propionic acid, delta lactone in amounts between about 0.0001 and 2.0 percent, and advantageously in amounts between about 0.0001 and 0.05 percent, by weight of the tobacco will enhance the flavor of the tobacco and improve organoleptic qualities of the tobacco smoke.

To help those skilled in the art further appreciate the invention, the following example is given:

EXAMPLE

A keto ester having the chemical structure

is formed by reaction of cyclohexanone with methyl acrylate in a Michael condensation. A keto acid having the structure

is formed from the aforesaid keto ester by saponification. A solution of 0.11 mole of the keto acid, 0.115 mole of sodium hydroxide and 0.05 mole of sodium borohydride in 100 milliliters of methanol is stirred under a nitrogen atmosphere for 4 hours at 0°C. This solution is then acidified, saturated with ammonium sulfate and thereafter extracted with ether. The ethereal extract is then washed with an aqueous solution of sodium bicarbonate, dried and concentrated. Distillation separates 68 percent of the product which is identified as 3-(2-hydroxycyclohexyl) propionic acid, delta lactone. This lactone consists of approximately 60 percent of the trans isomer and 40 percent of the cis isomer.

The resulting 3-(2-hydroxycyclohexyl) propionic acid, delta lactone is dissolved in ethyl alcohol and sprayed on shredded and blended domestic tobacco in amounts of 0.005 percent of the lactone by weight of the tobacco. After the ethyl alcohol is evaporated from the treated tobacco, cigarettes are made having a standard cellulose acetate filter. A second quantity of shredded and blended tobacco is sprayed with the same relative quantity of ethyl alcohol. After the ethyl alcohol is evaporated from the tobacco, cigarettes are made having a standard cellulose acetate filter. These cigarettes are used as the control for testing purposes. When compared to the control cigarettes, the 3-(2-hydroxycyclohexyl) propionic acid, delta lactone-treated cigarettes show a distinct improvement in the tobacco's flavor and aroma and the tobacco smoke's organoleptic properties. Procedures for making the above noted lactone contemplated by this invention are described in Vol. 62, pages 283-287 of the Journal of the American Chemical Society, and Vol. 27, pages 4141 to 4146 of the Journal of Organic Chemistry.

It should be understood that the term "tobacco product" as used herein are products made from tobacco such, for example, as cigarettes (either filtered or unfiltered), pipe tobacco and cigars. The lactone flavor additive may also be added to reconstituted tobacco or tobacco substitutes. It is also evident that the lactone contemplated by this invention may be added not only to the tobacco or filter tip section of a tobacco product but also to the cigarette paper wrapper or seam paste employed on the cigarette paper, or to the packaging material for the tobacco product. It is advantageous, however, that the lactone additive be included in the blended and shredded tobacco prior to its formation into a tobacco product.

We claim:

1. A tobacco product having added thereto a small amount of a lactone having the chemical structure

50

55

such amount being sufficient to enhance the flavor or aroma of the tobacco product.

2. A tobacco product in accordance with claim 1 wherein the lactone is present in amounts of about 0.0001 to 2.0 percent by weight of the tobacco.

3. A tobacco product in accordance with claim 2 wherein the lactone is present in amounts of about 0.0001 to 0.05 percent by weight of the tobacco.
